US0D1084340S

(12) **United States Design Patent** (10) **Patent No.:** **US D1,084,340 S**
(45) **Date of Patent:** **** Jul. 15, 2025**

(54) **RADIATION THERAPY DEVICE**

- (71) Applicant: **Hitachi High-Tech Corporation**,
Tokyo (JP)
- (72) Inventors: **Masayuki Arakawa**, Tokyo (JP); **Yuta Kawaguchi**, Tokyo (JP); **Yu Saitoh**,
Tokyo (JP); **Takashi Ishizuka**, Tokyo (JP)
- (73) Assignee: **Hitachi High-Tech Corporation**,
Tokyo (JP)
- (**) Term: **15 Years**
- (21) Appl. No.: **29/886,318**
- (22) Filed: **Mar. 7, 2023**

(30) **Foreign Application Priority Data**

- Oct. 31, 2022 (JP) ..... 2022-023696 D

(57) **CLAIM**

The ornamental design for a radiation therapy device as shown and described.

DESCRIPTION

FIG. 1 is a front, top and right side perspective view of a radiation therapy device according to the design;
FIG. 2 is a rear, top and left side perspective view thereof;
FIG. 3 is a front view thereof;
FIG. 4 is a rear view thereof;
FIG. 5 is a right side view thereof;
FIG. 6 is a left side view thereof;
FIG. 7 is a top plan view thereof;
FIG. 8 is a bottom plan view thereof;
FIG. 9 is a cross-sectional view taken along line 9-9 of FIG. 3;
FIG. 10 is a cross-sectional view taken along line 10-10 of FIG. 3; and,
FIG. 11 is a cross-sectional view taken along line 11-11 of FIG. 3.
The broken lines illustrate portions of the radiation therapy device that form no part of the claimed design.

1 Claim, 8 Drawing Sheets
